[57] CLAIM

The ornamental design for a table-top tripod, as shown and described.

DESCRIPTION

FIG. 1 is the perspective view of a design for table-top tripod showing my design;

FIG. 2 is the front elevational view thereof;

FIG. 3 is the rear elevational view thereof;

FIG. 4 is the left side elevational view thereof;

FIG. 5 is the right side elevational view thereof;

FIG. 6 is the top plan view thereof; and,

FIG. 7 is the bottom plan view thereof; and,

FIG. 8 is the perspective view thereof.

The broken line showing of a camera is for illustrative purposes only and forms no part of the claimed design.
